UNITED STATES PATENT OFFICE.

JOHN F. LEVAN, OF ELKHART, INDIANA, ASSIGNOR TO THE ADAMS & WESTLAKE COMPANY, OF CHICAGO, ILLINOIS, A CORPORATION OF ILLINOIS.

VENTILATING EAVES.

Application filed March 11, 1927. Serial No. 174,509.

This invention pertains to the ventilation of closed automobiles, and is particularly concerned with the construction of the so-called ventilating eaves which are applied to the 5 sides of automobiles over the frequently open upper portions of the windows.

The principal object of the invention is to provide a novelly constructed ventilating eave which is pleasing in appearance, inexpensive to manufacture, and easy to apply, the strip of glass or other material forming the eave proper being readily inserted in or removed from the end brackets by but one person without the use of any tools.

15 While the foregoing statement is indicative in a general way of the nature of the invention, other objects and advantages will occur to those skilled in the art upon a full understanding of the construction of the improved 20 ventilating eave.

One form of the invention is presented herein for the purpose of exemplification, but it will of course be appreciated that the invention is susceptible of embodiment in other structurally different forms coming 25 equally within the scope of the claims.

In the accompanying drawing:

Fig. 1 is a fragmentary side view of a closed automobile equipped with the ventilating eaves of the invention;

Fig. 2 is a vertical section, taken on the line 2-2 of Fig. 1;

Fig. 3 is a partly vertical and partly inclined section, taken on the line 3-3 of 35 Fig. 2;

Fig. 4 is a horizontal section, taken on the line 4-4 of Fig. 2; and

Fig. 5 is a perspective view, showing one of the end brackets.

40 The ventilating eave illustrated in the drawing consists of a narrow strip 10 of glass or other suitable material, and two brackets 11 having inclined seats 12 for supporting the ends of the strip. The brackets 11 are secured by screws 13 to the upper portions of the jambs 14 of the window opening, and the strip 10 is sealed within the seats 12 in the brackets and against the lintel 15 of the opening by a U-shaped rubber edging 45 applied to the edges of the strip.

50 Each of the brackets 11 consists of a generally triangular plate 17 having a flange 18 along one edge, and another slightly smaller plate 19 positioned against the plate 17 and having a flange 20 along one edge in

spaced generally parallel relation to the flange 18, whereby to form between such flanges the inclined seat 12. The plate 19 is preferably spot-welded or soldered to the plate 17, but may be held against the same 60 solely by the action of the screws 13 in holding the bracket against the jamb.

The plate 19 is made of spring metal, and the lower portion of the flange 20 on the same is disconnected from the plate along one 65 edge by a slot 21, thereby forming of the lower portion of the flange 20 a laterally deflectible spring tongue 22. The lower extremity of the tongue 22 is bent abruptly towards the flange 18 to form a hook-like 70 abutment 23 upon which the lower edge of the end of the strip 10 seats, and is bent downwardly beyond such abutment to provide a small tab 24 which may be grasped in deflecting the tongue laterally during insertion or removal of the end of the strip 10 from the seat 12 in the bracket.

75 The novel bracket construction, above described is not only pleasing in appearance and inexpensive to manufacture, but renders 80 the application of a ventilating eave incorporating the same exceedingly easy, since the two brackets may first be applied permanently to the jambs with the screws 13 and then the strip may be positioned within the 85 seats in the brackets by one person, without assistance, by merely pressing the tabs 24 to deflect the spring tongues 22 laterally and then sliding the ends of the strip up into the seats. When the ends of the strips have been 90 slid far enough into the seats to fully occupy the same, the lower edges of the ends of the strip will clear the abutments 23 on the spring tongues and such tongues will spring back again to bring the abutments 23 beneath the 95 lower edges of the ends of the strip, thus providing downwardly non-yieldable stops for the strip which may be readily deflected when occasion requires to permit removal of a broken strip and replacement by a new one.

100 I claim:

1. A ventilating eave for application to a window of a closed automobile, consisting of a strip of glass or other material, and two brackets having inclined seats in which the 105 ends of the strip are adapted to be positioned; said seats including abutments for the lower edges of the ends of the strip which are shiftable in a direction substantially at right angles to the plane of the glass into positions 110

clear of the lower edges of the same to permit removal of the glass.

2. A ventilating eave for application to a window of a closed automobile, consisting of a strip of glass or other material, and two brackets having inclined seats in which the ends of the strip are adapted to be positioned; said seats including abutments for the lower edges of the ends of the strip which are 5 deflectible in a direction substantially at right angles to the plane of the glass into positions clear of the lower edges of the same to permit removal of the glass.

3. A ventilating eave for application to a window of a closed automobile, consisting of a strip of glass or other material, and two brackets having inclined seats in which the ends of the strip are adapted to be positioned; said seats including spring abutments for the 10 lower edges of the ends of the strip which are yieldable in a direction substantially at right angles to the plane of the glass into positions clear of the lower edges of the same to permit removal of the glass but are non-yieldable 15 downwardly in such plane.

4. A ventilating eave for application to a window of a closed automobile, consisting of a strip of glass or other material, and two brackets having inclined seats in which the 20 ends of the strip are adapted to be positioned; each of said brackets being composed of a plate having a flange along one edge, and a spring member secured to the plate in spaced 25 relation to the flange and bent laterally adjacent its lower end to provide an abutment for the lower edge of the end of the strip which is deflectible in a direction substantially at 30 right angles to the plane of the glass into a position clear of the lower edge of the same 35 to permit removal of the glass.

5. A ventilating eave for application to a window of a closed automobile, consisting of a strip of glass or other material, and two brackets having inclined seats in which the 40 ends of the strip are adapted to be positioned; each of said brackets being composed of a plate having a flange along one edge, a spring 45

member secured to the plate in spaced parallel relation to the flange and bent laterally adjacent its lower end to provide an abutment 50 for the lower edge of the end of the strip which is deflectible in a direction substantially at right angles to the plane of the glass into a position clear of the lower edge of the same 55 to permit removal of the glass.

6. A ventilating eave for application to a window of a closed automobile, consisting of a strip of glass or other material, and two brackets having inclined seats in which the ends of the strip are adapted to be positioned; 60 each of said brackets being composed of a plate having a flange along one edge, and a second plate secured against the first plate and having a flange along one edge in spaced 65 parallel relation to the flange on the first plate, the flange on the second plate being free along one edge from that plate for a portion of its length and being bent laterally at its free end to provide a laterally deflectible 70 abutment for the lower edge of the end of the strip.

7. A ventilating eave for application to a window of a closed automobile, consisting of a strip of glass or other material, and two brackets having inclined seats in which the 75 ends of the strip are adapted to be positioned; each of said brackets being composed of a generally triangular plate having a flange along one edge, and a second generally triangular plate secured against the first plate 80 and having a flange along one edge in spaced parallel relation to the flange on the first plate, the flange on the second plate being free along one edge from that plate for a portion 85 of its length and being bent first laterally at its free end to provide a laterally deflectible but downwardly non-yieldable abutment for the lower edge of the end of the strip and then downwardly to provide a tab for use in deflecting the abutment.

In testimony whereof I have hereunto subscribed my name.

JOHN F. LEVAN.
